STEAM IRON WITH THERMALLY-OPERATED VALVE

Otto P. Pratt, Elgin, Ill., assignor to McGraw-Edison Company, a corporation of Delaware

Application February 24, 1954, Serial No. 412,238

2 Claims. (Cl. 38—77)

This invention is concerned with a steam iron, and more particularly with a water valve for a flash boiler type steam iron.

In the flash boiler type of steam iron, water from a storage tank is metered into a heated evaporating chamber where it flashes into steam substantially instantaneously. Heretofore water often has started to run into the evaporating chamber from the storage tank before the evaporating chamber has been heated to a high enough temperature to cause the water to flash into steam. When steam is generated in evaporating or steam generating chambers with an excess of water, such being the case when water enters the chamber before it has reached steaming temperature, droplets of water are likely to be carried out of the iron with the steam. Furthermore, after reaching proper steaming temperature the iron may be cooled by application to excessively wet work. Many types of fabrics, such as silk and rayon, are spotted by water drops, and it thus will be apparent that it is highly undesirable for water drops to be carried from the iron with the steam.

Accordingly, it is an object of this invention to provide a flash boiler type steam iron wherein no water enters the steam generating chamber until this chamber has reached the proper temperature for generating steam, and then only so long as it is maintained at such temperatures.

More particularly, it is an object of this invention to provide, in a flash boiler type steam iron, a thermostatically controlled valve preventing entrance of water into the steam generating chamber except when the steam generating chamber is at steam generating temperature.

A further object of this invention is to provide a flash boiler type steam iron wherein the soleplate of the iron is used as part of the steam generating chamber and as part of a thermostatic valve allowing entrance of water to the steam generating chamber only when said chamber is at steam generating temperature.

Yet another object of this invention is to provide a flash boiler type steam iron wherein a thermostatic valve controls entrance of water to the steam generating chamber, and said valve is not adversely affected by the presence of relatively cool water.

A still further object of this invention is to provide, in a flash boiler type steam iron, a thermostatic valve for controlling entrance of water into the steam generating chamber, which valve is afforded a quick opening action by contact of the first entering water with one of the thermostatic elements.

Other and further objects and advantages of the present invention will be apparent from the following description when taken in connection with the accompanying drawings wherein:

Fig. 1 is a side elevational view of an iron constructed in accordance with the principles of this invention, and with a part thereof broken away to show the filler tube and its cooperation with the thermostatic valve;

Fig. 2 is a fragmentary longitudinal sectional view through the iron with the valve in closed position;

Fig. 3 is a fragmentary view similar to a portion of Fig. 2 and showing the valve in opened position; and

Fig. 4 is a detail view of a part of a valve.

2

Referring now in greater particularity to the drawings, my invention will be seen to comprise a steam iron 10 having a body portion including a sheet metal case 12 of more or less usual design, and a soleplate 14. A handle 16 which preferably is molded of a thermal insulating plastic is suitably affixed to the top of the casing 12. The handle is provided with a substantially upright filler tube 18 extending through the forward portion thereof and comprising a cylindrical tube 20 and a bushing 22 at the upper end thereof, said bushing being threaded into the handle.

The bottom end of the filler tube 18 extends into a reservoir or water storage tank 24 to which it is brazed or welded as indicated at 26. The tank 24 is supported within the body casing 12 at the forward end by a valve structure 28 later to be described in detail, and at the rear end by a bracket (not shown). Suitable means is provided for heating the soleplate and this means is illustrated as an electric resistance heating element 32 of known construction cast in place in the soleplate. The heating element is controlled by a suitable thermostatic mechanism 34, and the temperature at which the thermostatic mechanism operates is determined by a suitable setter or pointer 36 extending above the body casing 12 from beneath the rear portion of the handle 16. This pointer cooperates with a suitable dial 38 indicating the various types of fabrics which may be ironed.

The valve structure 28, previously mentioned, extends from the front end of the water storage tank or reservoir 24 down into an evaporating or steam generating chamber 86. The steam generating chamber is formed by a recess 88 in the soleplate, and a sheet metal plate 90 secured across the top of the recess by any suitable means such as a plurality of screws 92. The sheet metal plate 90 preferably is braced near the valve 28 by a post 94 upstanding from the floor of the evaporating chamber, and a screw 96 is passed through the plate and threaded into this post. The recess 88 is provided with a ledge or shoulder 98 having a plurality of protuberances or bosses 100 thereon. Apertures or bores 102 extend from the tops of these bosses 100 entirely through the soleplate and out the bottom thereof for the passage of steam from the evaporating surface 104.

The valve 28 comprises an externally threaded cylinder 106 extending through suitable openings in the bottom of the water tank or reservoir 24 and in the sheet metal plate or cover 90 of the steam generating chamber. The cylinder 106 is provided with an integral external collar or ring 108 lying between the reservoir and steam generating chamber, and sealing rings, washers, or gaskets 110 and 112 are interposed between this collar or ring and the reservoir and steam generating chamber. A nut 114 threaded on the top of the cylinder 106 clamps the bottom of the reservoir against the sealing ring 110 and the collar 108, and a nut 116 threaded on the bottom end of the cylinder 106 clamps the cover or plate 90 against the sealing ring 112 and collar 108. It will be noted that the valve 28 is aligned with the opening through the filler tube 18 so that a wrench can be slipped through the filler tube to tighten the nut after assembly.

An opening or bore 118 extends axially through the cylinder 106, and is beveled or flared outwardly at the ends thereof so as to form a lower valve seat 120. The bevel at the top facilitates entrance of water into the valve when the water level in the reservoir is low, and it further affords a symmetrical construction simplifying initial assembly in that the valve may be inserted with either end up, and providing prolonged valve life in that the cylinder 106 can be inverted if the valve seat 120 becomes worn.

The soleplate 14 preferably is made of aluminum or aluminum alloy. A bowed strip 122 of material having

a coefficient of expansion lower than aluminum is positioned in the steam generating chamber with the ends of the strip affixed to the evaporating surface 104 of the soleplate by fasteners 124 which may be screws, or any other suitable fasteners. A split, threaded stud 126 extends through the bowed strip and is spot welded thereto as indicated at 128 in Fig. 4. The legs of the split stud are spread slightly apart so that the threads on the stud will frictionally grip the internal threads 130 of a valve closure member 132 having a beveled surface 134 engageable with the valve seat 120 to close the valve. The valve closure member 132 is provided with a stem 136, and the top of this stem is provided with a slot 138 for a screw driver adjustment of the valve closure member.

The valve closure member 132 is adjusted with a screw driver extending through the filler tube 18. Preferably it is so adjusted that the valve begins to open at 250° F. Then at lower temperatures member 132 will buckle slightly, and the valve is closed as indicated in Fig. 2. When the iron heats up, the aluminum soleplate expands at a faster rate than the strip 122. This tends to pull the ends of the strip away from one another, and thus the strip is partially flattened out. As the strip flattens, it withdraws the valve closure member 132 from the valve seat 120 to allow water to pass from the reservoir into the steam generating chamber. The water in the reservoir being below 212° F. is cooler than the soleplate, and when it enters the steam generating chamber it encounters the strip 122 and cools the strip slightly. This action contracts the strip somewhat and effects a more rapid opening of the valve.

The distance that the valve member 132 is withdrawn from its seated position depends on the temperature of the iron compared to the opening temperature, and whether or not there is water flowing. So long as the opening is so small that the seating parts 120 and 134 provide the principle control of the flow, the rate of flow will increase with the temperature of the soleplate. At larger separations the flow rate will be determined principally by the cylindrical bore 118 and stem 136, and will not increase materially with further rise of soleplate temperature. I prefer that the soleplate and steam chamber operate at about 325° for steam ironing of all fabrics, and for such operation I prefer that valve member 132 be adjusted to begin opening when the soleplate rises to about 250° F. and that the maximum rate of water flow be obtained with the soleplate at about 275° to 300° F. Of course, substantially the same maximum flow will be obtained at all higher temperatures. The valve is shown open in Fig. 3.

Alternatively steam ironing may be done with various soleplate and steam chamber temperatures. For such use the valve member 132 may be adjusted to provide a small water flow at some low temperature for fabrics such as nylon, acetate or rayon. At higher temperatures for fabrics such as wool, linen and cotton, the valve will open farther to provide a greater flow to utilize the higher steam generating capacity of the steam chamber at the higher temperature. For example, for such operation, water may begin flowing slowly when the soleplate has risen to 225° F., and may increase its flow rate gradually and provide maximum rate at a soleplate temperature of 350° to 375° F. The temperature difference between the temperature for initial opening and the minimum temperature for maximum flow will depend on the movement required of valve member 132, the specific materials of the soleplate and the strip 122, and the angle that strip 122 makes with the soleplate.

It previously has been noted that the soleplate 14 preferably is made of aluminum or aluminum alloy. This imparts a high coefficient of expansion to the soleplate, and it is comparatively easy to select a material for the strip 122 that will have a lower coefficient of expansion. Preferably, however, the strip is made of any of several commercially available alloys of nickel and iron. One

such alloy is available under a number of different trademarks and is composed of approximately 58% iron. This material has a coefficient of expansion about $\frac{1}{6}$ that of aluminum up to 600° or 700° F. An alloy of about 36% nickel and 64% iron, sold under the trademarks "Invar" and "Nilvar," has an even lower coefficient of expansion at temperatures below 350° F. In this temperature range, a coefficient of expansion of this material is about 4% that of aluminum. This temperature range is generally satisfactory inasmuch as flash type steam irons are usually operated at about 325° F. Furthermore, this alloy is not damaged at exposure to higher temperatures, such as 550° F., at which the iron may be used when operated dry.

It is obvious that the steam iron herein disclosed satisfies the objects of the invention. Water cannot enter the steam generating chamber from the reservoir unless the steam generating chamber is at steaming temperature. The thermostat valve is not subject to improper operation due to the cooling effect of the incoming water, but actually is operated more quickly as one part of the thermostat is contacted by the cool water. The degree to which the valve is opened can be determined in accordance with the operating temperature of the iron, and the rate of steam generation thereby made commensurate with the operating temperature of the iron and the requirements of the particular fabric being ironed. Since the soleplate is used as a part of the thermostat, the principal response of the valve necessarily is to the temperature of the soleplate itself. The valve used in this steam iron readily can be assembled and adjusted through the filler tube.

It will be understood that the particular structure herein shown and described is for illustrative purposes only. Various changes can be made and form a part of my invention insofar as they fall within the spirit and scope of the appended claims.

I claim:

1. A steam iron comprising a sole plate constituting one element of a thermostat and formed of a material having a relatively high coefficient of expansion, said sole plate having a recess therein forming a steam generating chamber with an evaporating base, means for heating the sole plate, means providing a water reservoir, a cover plate for the steam generating chamber, means providing a passage from the water reservoir through the cover plate and to the steam generating chamber, an upwardly bowed strip disposed in said recess and constituting the second thermostat element of a material having a relatively low coefficient of expansion and with the ends thereof secured directly to the evaporating base of the sole plate and confined within the steam generating chamber, and a valve member carried by the central portion of the bowed portion of said strip and positioned to cooperate with said passage to control the flow of water through said passage and said strip being at least partially disposed in the path of water flowing from the passage when the valve member is in open position whereby the strip is cooled to resist reclosing and chattering of the valves.

2. A steam iron as claimed in claim 1, wherein the valve member is mounted on the bowed strip by means of a split threaded stud extending through the bowed strip and into an internally threaded recess in the valve member whereby the position of the valve member with respect to the bowed strip may be adjusted.
